OIL DISPENSING CONTAINER

Filed June 14, 1938

UNITED STATES PATENT OFFICE

2,151,604

OIL DISPENSING CONTAINER

James I. Kushima, Ewa, Territory of Hawaii

Application June 14, 1938, Serial No. 213,725

2 Claims. (Cl. 221—19)

This invention relates to oil dispensing containers and has for its object to provide a container having a pivoted discharge spout associated with a rotatable valve whereby the discharge of oil from the container is controlled by the movement of the spout.

A further object of the invention resides in providing manually operated mechanism for moving the discharge spout to an operative position and returning the same to an inoperative position.

Another object of the invention resides in providing a device of the above-mentioned character which is simple and durable in construction, efficient in use, and inexpensive to manufacture.

Other objects and advantages of the invention will be apparent during the course of the following description.

In the accompanying drawing forming a part of this specification and in which like numerals are employed to designate like parts throughout the same,

Fig. 1 is a side elevation of the container with the discharge spout in an inoperative position,

Fig. 2 is a front elevation of the same with the spout in operative position,

Fig. 3 is a longitudinal sectional view taken on line 3—3 of Fig. 4, and

Fig. 4 is a transverse section taken on line 4—4 of Fig. 3.

In the drawing, wherein for the purpose of illustration I have shown a preferred embodiment of my invention, the numeral 14 denotes the container having a bottom 24 spaced upwardly from the lower end of the body and a hood 13 partially covering the upper end of the body to prevent spilling of the contents when the container is being carried. The bottom 24 is inclined downwardly towards the outlet elbow 6 depending from the bottom adjacent the wall of the body. A stationary valve disk 2 is threadedly attached to the free end of the elbow 6 and a rotatable valve disk 1 is connected to the stationary valve disk by a central bolt 15. An oil-tight connection is established between the valve disks by the leather washer 17 and the steel washer 18 disposed on opposite sides of the valve disk 1 which are held in place by the coil springs 16 and 19 mounted on the bolt and a nut 20 threaded on the end of the bolt permits tightening of the spring pressure to adjust the connection. An annular ridge 4 formed on the face of the disk 2 engages in a corresponding groove 5 in the face of the disk 1 to guide the rotation of the disk 1 and establish a perfect fit between the disks. A chamber 3 is threadedly connected to the valve disk 1 in alignment with the elbow 6 and openings 11 formed in the valve disks 1 and 2 are adapted at times to register to establish communication between the elbow and chamber.

An opening is formed in the side of the chamber 3 to permit access to the bolt 15 for adjusting the nut 20 and a plate 8 normally covers the opening being secured in place by screws 9. A discharge spout 10 extends from the side of the chamber 3 and projects through an opening in side wall of the container. The spout is curved upwardly and in its inoperative position, shown in Fig. 1, is parallel to the wall of the container. When the spout is in an inoperative position, the valve is closed but upon swinging the spout downwardly to the position shown in Fig. 2, the valve is opened permitting oil to flow from the container through the spout.

The spout is actuated by a reciprocating rod 15 which is mounted in openings formed in the handle 26, the lower end of the rod being pivotally connected to one end of the rock lever 32, pivotally mounted, as at 36. The opposite end of the lever 32 is connected by a connecting rod 20 to a lug 35 formed integral with the spout. An expansion spring 30 is mounted on the rod 27 between the washer 29 secured in place by a cotter pin 28 and the brace 31 extending between the handle and container. A stop pin 39 carried by the rotatable valve disk co-acts with the stops 37 and 38 carried by the stationary valve disk to limit the rotative movement of the valve and movement of the spout.

In operation, the container 14 is filled with oil and when it is desired to dispense the same, the rod 27 is depressed against the pressure of the spring 30 which rocks the lever 32 and through the connecting rod 34 swings the spout 10 downwardly. As the spout swings downward the valve disk 1 is rotated, so that the openings 11 of the valve disks 1 and 2 are brought into register which permits the oil to flow from the container and be discharged from the spout. Upon releasing the rod 27, the spring 30 expands and moves the rod upwardly to return the spout to its inoperative position.

It is to be understood that the form of my invention herein shown and described is to be taken as a preferred example of the same and that certain changes in the shape, size and arrangement of the parts may be made without departing from the spirit of the invention or the scope of the subjoined claims.

Having thus described my invention, I claim:

1. A dispensing container comprising a container having a bottom provided with an outlet elbow, a stationary valve disk secured to the end of said elbow, a rotatable valve disk, a bolt pivotally connecting said valve disks together, a chamber attached to said rotatable disk in alignment with said elbow, said valve disks having registerable openings for establishing communication between said elbow and chamber, a spout extending from the side of said chamber and

- projecting from said container adapted to swing in a vertical plane, a rod mounted to reciprocate outside of said container, a rock lever pivotally mounted in the lower end of said container having one end connected to said rod, a connecting link joining the opposite end of said lever to said spout, whereby downward movement of said rod causes said spout to swing downwardly, and a spring mounted on said rod normally urging said rod upwardly.
5. A dispensing container comprising a container having a bottom provided with an outlet elbow, a stationary valve disk secured to the end of said elbow, a rotatable valve disk, a bolt ex-

tending through the center of said valve disks pivotally securing said disks together, said valve disks having openings adapted at times to register, a chamber secured to said rotatable valve disk in alignment with said elbow, a spout extending from the side wall of said chamber through an opening in the wall of said container, said spout being curved to be parallel to the side of said container when swung upwardly, a 5
